UNITED STATES PATENT OFFICE.

WILLIAM M. CLARK, OF BOSCOBEL, WISCONSIN.

DESIGN FOR A BAG-TIE.

SPECIFICATION forming part of Design No. 29,853, dated December 20, 1898.

Application filed November 28, 1898. Serial No. 697,705. Term of patent 7 years.

To all whom it may concern:

Be it known that I, WILLIAM M. CLARK, a citizen of the United States, residing at Bos-
cobel, in the county of Grant and State of Wis-
consin, have invented and produced a new
and original Design for a Bag-Tie, of which
the following is a specification, reference be-
ing had to the accompanying drawings, forming
a part thereof, in which—

to Figure 1 is a perspective view of a bag-tie
embodimenting the features of my design, and
Fig. 2 is a transverse section on the line 2 2
of Fig. 1.

The design embodies an elongated open
loop-body A, contracted at its open end, both
members of the body at said open end being
bent to form an eye, and the eyes (designated
as B and B') are carried in opposite direc-

tions. A space intervenes the terminal of
each eye and the bow or body, and the eye B' 20
at its terminal is given a hook formation, the
hook being in the same vertical plane with
the end of the eye.

The leading feature of the design consists
in the elongated loop-body A, both members 25
of the body at its open end being bent to form
an eye, which eyes are carried in opposite di-
rections, one of said eyes having its terminal
bent to form a hook.

I claim—
30
The design for a bag-tie herein shown and
described.

WILLIAM M. CLARK.
